UNITED STATES PATENT OFFICE.

FRANK W. HUSSEY AND CHARLES H. DOTY, OF COLUMBUS, OHIO, ASSIGNEES TO THE KILBOURNE AND JACOBS MANUFACTURING COMPANY, OF COLUMBUS, OHIO, A CORPORATION OF OHIO.

TRUCK.

1,093,560.

Specification of Letters Patent. Patented Apr. 14, 1914.

Application filed June 20, 1912. Serial No. 704,762.

To all whom it may concern:

Be it known that we, FRANK W. HUSSEY and CHARLES H. DOTY, citizens of the United States, residing at Columbus, in the county 5 of Franklin and State of Ohio, have invented certain new and useful Improvements in Trucks, of which the following is a specification.

Our invention relates to improvements 10 signed especially for use on trucks of the style having one or two wheels at the forward end, and legs and handles at the rear end. It is, however, not confined to use in such a structure, as the features herein described 15 are applicable as well to the bed and frame of a four wheeled baggage or express truck; and we therefore do not confine the use of our invention to any particular style of truck.

20 The invention consists especially in an improved construction of sidesill combined with a nose portion preferably being integral therewith; also in an improved cross bar or bracing construction between the sidesills; also in an improvement in the construction for the positioning and fastening 25 of the handle pieces, which are preferably made of wood. These and other features of our construction will appear more clearly 30 in the description hereinafter given, in the claims.

In the drawings which are hereto attached, and hereby made a part of the specification, Figure 1 shows a top plan view of 35 a truck, embodying our improvements. Fig. 2 shows a side view of the truck in Fig. 1. Fig. 3 is a cross section showing the application of the leg braces to the cross bar between the sidesills. Fig. 4 shows one form 40 of construction for applying the cross bar to the side sill. Fig. 5 shows another form of construction for applying the cross bar to the side sill. Fig. 6 shows the construction for positioning and fixing the handle pieces. Fig. 7 shows the tie rod and bracing construction applied to the truck on a cross bar other than the rearmost one. Fig. 45 8 is a section along the line S—S of Fig. 1, showing the cross bar and tie rod forming 50 the connection between the side sills and the manner of uniting said bar and rod with the side sills.

Referring to the drawings, in which the same numeral indicates the same part throughout, 1 is a side sill of the truck 55 formed preferably of a pressed steel angle facing inwardly, the angle being shaped at one end to form the upturned portion 2, integral with the side sill. At its other end, the side sill has formed thereon the rectangular sleeve 3 for the reception of the wooden handle piece 4, which is slightly beveled or cut away on the inner end of the upper face thereof, as appears at 5, and is clearly illustrated in Fig. 6. The handle 65 piece 4 is inserted in the sleeve 3, and fits in the angle of the side sill 1, and is secured in place by the bolt 6; and as the nut 7 thereon is turned into place, this end of the handle piece is sprung upwardly (see Fig. 6) and 70 the engagement of the handle with the sleeve is thereby assured under all conditions. As the handle is likely to become more or less worn in its bearings by use, the provision of the bevel 5, in conjunction with 75 the bolt 6 assures a tightening means for the handle, which is a valuable feature for truck constructions. It is noted that the handle where it fits into the sleeve 3 is rectangular in cross section, and has preferably the 80 same form where it fits into the angle of the side sill 1, for the simple reason that a more secure application can be made to the sleeve and the angle of the side sill with that form of construction. 85

At 8 is shown a wheel having its bearing at 9 in the bearing member 10, which is applied to the angle of the side sill 1, and secured thereto by the bolts 11 and 12, in such manner that the bearing member 10 90 itself bears against the depending flange of the angle of the side sill, and is thereby supported against lateral movement.

The crossbars are shown at 13, 14, 15 and 16, and the straps 17 and 18 are placed longitudinally of the truck and applied to the cross bars, not only to aid in forming the truck platform, but also for the purpose of strengthening the same. The cross bars are preferably formed of a channel, having its 95 depending flanges made in truss form, as especially appears by reference to Fig. 3, in which the cross bar 16 is shown with the depending flange trussed, as appears espe- 100

cially at 19. The purpose of the truss is obviously to strengthen the cross bar and render it more capable of supporting the heavy loads which such trucks are usually required 5 to carry.

Referring especially to Fig. 4, the channel cross bar 20 is shown applied to the angle of the side sill 21 by means of the lugs 22 and 23, extending laterally from the end of the 10 channel, and being secured through the depending side flange of the angle by the bolts or rivets shown especially at 24. The channel is also secured to the horizontal flange of the side sill 21 by means of the rivet shown at 25, disclosed by breaking away the flange of the cross bar.

In Fig. 5 is shown an optional construction for applying the channel cross bar to the side sill, which construction is illustrated 20 also in Fig. 3. In this form the channel 16 has a lug 26 formed at its end which is inserted through side sill opening 40 and secured by the rivet 27 (Fig. 3); the opening 28 receives the tie rod 30 as hereinafter set 25 forth.

Referring especially to Fig. 3, we employ with as many of the cross bars as desired a tie-rod 30, which passes through the side sills at its ends and is secured in place by 30 means of the nuts 31 and 32. The tie rod lies within the channel cross bar 16 and the leg braces 33 and 34 are inserted at their upper ends into the channel and are secured thereto by the bolts 35 and 36. Said leg 35 members are each provided with an opening shown at 37 and 38 through which the tie rod 30 is passed, and these openings 37 and 38 are in a lower plane than the openings 28 and 29 formed through the side sills for the 40 reception of the tie rod 30. The effect of passing the tie rod 30 through said openings, two of which lie in one plane and two of which lie in a lower plane, is to truss the rod 30, whereby its bracing and strengthening effect on the side sills is increased.

Referring especially to Fig. 7, there is illustrated the tie rod 41, which is used in connection with the cross bar 15, and in this construction the truss effect on the rod 41 is 50 produced by the bridge 42, fitted into the channel of the cross bar 15 preferably at its middle point. It is apparent that two or more bridges might be used, but such construction would merely multiply parts and 55 increase cost without giving a proportionate additional degree of strength. Therefore, we show as the preferable construction only one bridge in each cross bar for the purpose of trussing the tie rod used therewith. It is 60 not deemed necessary to illustrate the entire length of the cross bar and tie rod in Fig. 7, and they are therefore shown broken away at their ends, the purpose being merely to 65 illustrate the application of the bridge member. Reference to Figs. 3 and 8 will disclose

the complete construction and connections for the cross bar and the tie rod with each other, and with the side sills.

Referring especially to Fig. 2, the construction of the leg is shown formed preferably of the member 43 secured to the side sill at 44, and the member 45 which is secured to the sleeve 3 by the countersunk bolt 46. The leg therefore at both of its ends is connected with the side sill and has no association with the handle piece 4. In the apex 47, formed by the leg members 43 and 45, is secured one end of the leg brace 33 by means of the bolt or rivet 49.

Preferably the tie rod is omitted in connection with the cross bar 13, the rearward flange of which is cut away at its ends to admit the extension 50 of the wheel bearing member 10, said extension 50 therefore being seen to be braced laterally both by the side sill 1 and the abutting flange 51, from which a portion has been removed to accommodate the extension 50.

Referring to Fig. 1, the nose bar 52 is shown secured to the upturned ends 2 and 2^a of the side sills, the bar 52 being welded or brazed or secured in whatever manner may be preferable.

The prominent features of our truck construction are adapted to a variety of trucks, and consist especially in the use of the various features pointed out, namely, the angle side sill bent upwardly at one end and having a sleeve formed at its other end for the reception of the handle piece; the handle piece slightly beveled on the upper face of its inner end, which provides for the adjustment of the securing means at will to render the handle at all times perfectly tight and secure; the trussed channel cross bars secured to the side sills either with lateral or horizontal lugs formed on the crossbar, and the truss tie rod associated with the cross bar, the truss effect being produced in the rearmost cross bar by the leg braces 100 themselves, and in the other cross bars by the use of a bridge; the application of the leg members wholly to the side sill, instead of connecting them with the wooden handle pieces, our construction affording greater 105 strength and simplicity; and lastly, the cutting away of one of the flanges on one of the cross bars at the ends to accommodate the wheel bearing members, which are applied to the side sill.

We do not confine ourselves to the specific forms of construction illustrated and described, but desire to have the advantage of any construction falling within the scope of the appended claims.

What we claim is:

1. In a truck an angle sidesill having a rectangular sleeve formed at one of its ends, a handle piece constructed to be inserted into said sleeve and applied to the flanges of 130

said side sill, the upper face of the inner end of said handle piece being beveled, and means for adjustably securing the inner end of said handle piece to the side sill.

5 2. In a truck having angle sidesills facing inwardly, a channel crossbar secured at its ends to said sidesills, leg braces secured at one end to said crossbar, and a tie rod secured at its ends to said sidesills and being engaged by said leg members to truss said tie rod.

10 3. In a truck an angle side sill having a sleeve formed at one end thereof, a handle piece adapted for insertion into said sleeve

and the angle of said side sill, and means for 15 springing said handle into adjustable engagement with the said sleeve and said side sill.

In witness whereof we have hereunto subscribed our names at Columbus, Ohio, on 20 this 17th day of June, 1912, in the presence of two witnesses.

FRANK W. HUSSEY.
